(74) Attorney, Agent, or Firm — Jeffer Mangels Butler & Mitchell LLP; Brennan C. Swain, Esq.

(57) **CLAIM**

The ornamental design for a rechargeable battery assembly as shown and described.

DESCRIPTION

FIG. 1 is a perspective view of the rechargeable battery assembly, showing my new design;

FIG. 2 is a front side elevational view thereof;

FIG. 3 is a rear side elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines shown in the drawings illustrate portions of the rechargeable battery assembly that form no part of the claimed design.

1 Claim, 4 Drawing Sheets(56)
